UNITED STATES PATENT OFFICE.

GEORGE C. KEENE, OF CINCINNATI, OHIO, ASSIGNOR OF TWO-THIRDS TO
LONGLEY LEWIS SAGENDORPH AND HARLAN P. LLOYD, BOTH OF SAME
PLACE.

MACHINE FOR CRIMPING SHEET METAL.

SPECIFICATION forming part of Letters Patent No. 364,259, dated June 7, 1887.

Application filed April 7, 1887. Serial No. 233,980. (No model.)

To all whom it may concern:

Be it known that I, GEORGE C. KEENE, a resident of Cincinnati, in the county of Hamilton and State of Ohio, have invented certain new and useful Improvements in Machines for Crimping Sheet Metal, of which the following is a specification.

The various features of my invention and the advantages resulting from their use, con- 10 jointly or otherwise, will be apparent from the following description.

In the accompanying drawings, forming part of this specification, Figure 1 is a front elevation of my machine. Fig. 2 is an end elevation of a machine embodying certain features of my invention. Fig. 3 is a vertical cross-section taken at the line X X, Fig. 1. Fig. 4 is an elevation of the opposite side of the bracket-arm from that shown in Figs. 2 and 3. Fig. 5 is a top view of the parts shown in Fig. 4. Fig. 6 is a vertical section of a modification of my machine, showing double dies and the machine in the position of forming the first crimp. Fig. 7 shows the lower part 25 of the section shown in Fig. 6, the parts being in the position of forming the second crimp. Fig. 8 is a top view of one end of the front die and supporting-table.

I will first proceed to describe the mechanism illustrated in Figs. 1 to 5, inclusive.

The frame A is made in such a way as to properly support the operating parts of the machine. From the longitudinal beam B the crimping-bar C is suspended by means of toggle-arms D. The toggle-arms are united to a central connecting-rod, E, to which a reciprocating horizontal movement is imparted by means of a cam or eccentric, F. This cam receives its motion through a series of gear-wheels from the crank-wheels G. The flanges a, projecting from the ends of the frames, serve as guides for the crimping-bar. The longitudinal die H is attached to the lower face of the crimping-bar C. Immediately under the die H is the female die I, which is supported by the frame-work A.

To the rear of the frame A is placed a longitudinal guide or gage, J, which is adjusted with reference to the die I by means of the set-

screws J'. Two or more bracket-arms, K, are 50 bolted to the front of the frame-work and project forwardly. The rail L is supported on the ends of the bracket-arms K, and extends lengthwise of the machine parallel to the dies. This rail L is provided with grooves l, 55 conforming in shape to the crimps formed by the several dies used in the machine. The rail L is movable on the bracket-arms K in the direction of the length of the arms. Its movement toward the dies is governed by two 60 set screws, M, one on each bracket-arm. Each set screw passes through a lug, m, projecting upwardly from the top of the bracket-arm. The forward movement of the rail L is similarly limited by set-screws N.

The set-screws N are screwed through lugs n, projecting from the bracket-arms, and impinge against lugs l', projecting downwardly from the rail. The rail L is also provided with two downwardly-projecting lugs, 7c 75 l'', each of which passes through a slot, k, in bracket-arm K. This serves to hold the rail to the arms, or at least to prevent longitudinal displacement of the rail. A spring, O, is stretched between the front end of each bracket-arm and the lug l''. These springs O tend to keep the rail L against the ends of the front set-screws, N. My machine is also preferably provided with a second rail, P, supported on the bracket-arms parallel to the rail L and 80 about midway between the rail L and the dies. This rail P is also preferably provided with adjustable set-screws and springs, as already described for the rail L.

As illustrated in Figs. 6, 7, and 8, I sometimes provide the machine with two sets of toggle-arms and dies instead of one. In this modification the second set of arms is preferably operated by an eccentric on the same shaft with the eccentric for the other set of arms; but they may be operated by independent mechanism. In this modification the rail L, receiving the thrust of a male die, is preferably mounted on a more solid support than the bracket-arms K, such as an I-girder. The 95 set-screws N, as well as the set-screws M, are placed on the upper surface of the girder. The springs O, for drawing the rail L against

the set screws N, are also placed above the girder instead of under it. To guide the rail L in its movements I provide it with a number of lugs, T, each having a slot, t, through 5 which a screw, T', passes into the girder.

The mode of operation of my machine is as follows: A sheet of metal is laid on the machine, resting on the rails L and P and the lower die, I. It is adjusted in position by being pushed against the gage J. The upper die is now lowered by turning the crank-wheels G, and, forcing the metal into the lower die, forms the desired crimp. This crimp is formed from metal drawn from both sides of 10 the die. The sheet is now removed and reversed and again placed in the machine. This time it is secured in proper position by dropping the formed crimp in the correspondingly-shaped groove l in the rail L, the rail having 15 been previously properly adjusted by the set-screws N. The sheet in this position is held firmly and the necessity of special clamps dispensed with. The crimping-bar is again brought down and forms a crimp in the other 20 edge of the sheet. As the upper die descends it forces the metal into the lower die, drawing it from both sides of the die. This movement of the sheet is accommodated by rail L, which is drawn toward the dies against the tension 25 of the springs O. The amount of movement of the rail L toward the dies is limited by the set-screws M. The sheet is now removed from the machine, and the springs O return the rail L to its place against the set-screws N. When 30 it is desired to crimp the center of the sheet, one of the edge-crimps is dropped in the groove in the rail P, which serves as a guide, while the die is forced down on the sheet.

In the modification shown in Figs. 6, 7, and 40 8 the sheet Q is placed in position against the gage J, and the front die, H, first descends and forms the first crimp, the die H' being meanwhile elevated. The die H now rises and the die H' descends and forms the second crimp, 45 and the rail L moves against the tension of the springs O and takes the position shown in Fig. 7. The operation of the rail L and the function it performs are the same in the present instance as that already described in the operation 50 of the mechanism shown in Figs. 1 to 5, inclusive.

The principal advantage of my machine is the tension device, which is so arranged as to allow of the use of a cheap and low grade of 55 sheet metal without tearing it in crimping.

The readiness with which the sheets are put in position is another feature of importance.

What I claim as new, and desire to secure by Letters Patent, is—

1. In a machine for crimping sheet metal, a 60 sliding guide-rail, in combination with crimping-dies, substantially as and for the purposes specified.

2. In a machine for crimping sheet metal, the sliding guide-rail L, provided with grooves 65 l and means for retracting the said rail, in combination with crimping-dies, substantially as and for the purposes specified.

3. In a machine for crimping sheet metal, the combination of the guide-rail L, suitably 70 supported and provided with groove l, and set-screw N, for limiting the movement of the rail L, and spring O, in combination with crimping-dies, substantially as and for the purposes specified.

4. In a machine for crimping sheet metal, the combination of the guide-rail L, suitably supported and provided with groove l, set-screws M and N, for limiting the movement of the rail L, and springs O, in combination with 80 crimping-dies, substantially as and for the purposes specified.

5. In a machine for crimping sheet metal, the combination of the movable guide rails L and P, provided with grooves to receive the 85 crimps, in combination with crimping-dies, substantially as and for the purposes specified.

6. In a machine for crimping sheet metal, the combination of crimping-dies and sliding guide-rail L, provided with grooves l, of different shapes, and means for retracting the said rail, substantially as and for the purposes specified.

7. In a machine for crimping sheet metal, the combination of the dies H and I, with 95 means for operating the same, the sliding guide-rail L, provided with grooves l and means for retracting the said rail, and the sliding guide-rail P, provided with groove l and means for retracting said rail, substantially as 100 and for the purposes set forth.

8. In a machine for crimping sheet metal, the combination of the male dies H H', mechanism for operating the same, female die I, and movable female die L, substantially as and 105 for the purposes specified.

GEORGE C. KEENE.
